PROCESS CONTROLLER

Roger B. Kerr, Topsfield, Mass., assignor to General
Electric Company, a corporation of New York

Filed June 20, 1963, Ser. No. 75,445

Term of patent 14 years

(Cl. D26—1)

The figure is a perspective view of a process controller showing my new design.

The essential features of my design reside in the portion shown in solid lines.

I claim:

The ornamental design for a process controller, as shown and described.
